ROTARY PUMP

James P. Johnson, Shaker Heights, Ohio

Application January 18, 1950, Serial No. 139,261

13 Claims. (Cl. 103—161)

1

The present invention relates generally as indicated to rotary pumps and more particularly to rotary pumps of the character which include pump members interconnected generally in the manner of an Oldham coupling or in other words a sliding coupling for parallel shafts.

It is one primary object of this invention to provide rotary pumps which may be operated at high speeds and low temperatures because of the elimination to a great degree of high-speed sliding or rubbing contacts between the displacement chamber forming elements thereof.

As a further object of this invention, also imputed to the aforesaid elimination of high-speed rubbing contacts, is the capability of the use of the present pumps with fluids such as air or other fluids which do not have lubricating properties whereas in the common forms of gear, sliding vane, screw, and like pumps of the positive displacement type, the friction between sliding surfaces is considerable thus restricting the use of the last-mentioned type of pumps to use with oil or other liquids which have lubricating properties. Moreover, pumps of the last-mentioned type require the maintenance of extremely close fits between the rubbing surfaces in order to achieve a reasonable volumetric efficiency thereby further restricting the use of these pumps to use with fluids which have sufficient viscosity to prevent excessive leakage.

Therefore, another object of this invention is to provide rotary pumps which are so formed that the opposed and relatively moving surfaces of the displacement chamber forming elements need not be extremely closely fitted, that is, sizable clearances may be maintained without corresponding loss of volumetric efficiency.

Another object of this invention is to provide rotary pumps in which the bearing loads are at least semi-balanced.

Another object of this invention is to provide rotary pumps in which the peripheral wall of the pump casing chamber is of unique shape and simple to form as compared with the usual walls of vane pumps which include generally elliptical, limacon, Archimedes' spiral, or other special sections which are difficult to generate.

Other objects and advantages will become apparent as the following description proceeds.

To the accomplishment of the foregoing and related ends, said invention, then, comprises the features hereinafter fully described and particularly pointed out in the claims, the following description and the annexed drawing setting forth in detail certain illustrative embodiments of the

2

invention, these being indicative, however, of but a few of the various ways in which the principle of the invention may be employed.

In said annexed drawing:

5 Fig. 1 is a cross-section view diametrically across one embodiment of the present invention;

Fig. 2 is an exploded perspective view of the pump assembly which is adapted to be rotatably fitted within a pump casing;

10 Fig. 3 is a cross-section view taken substantially along the line 3—3, Fig. 1, illustrating one rotative position of the pump assembly in the pump casing;

Fig. 4 is a cross-section view similar to Fig. 3 except showing the pump assembly in a different rotative position; and

Fig. 5 is a cross-section view similar to Fig. 1 illustrating a modification.

Referring now more specifically to the drawing and first to Fig. 1, there is shown therein a pump casing part 1 of generally tubular form provided with a cylindrical bore 2 formed with axially spaced undercuts 3 and 4 from which lead the passages 5 and 6 to the respective ports 7 and 8 in said casing part.

Secured to said casing part 1 as by bolts or other suitable means (not shown) is a casing part or head 9 which defines with said casing part 1 a cylindrical chamber comprising the bore 2 and opposed parallel end walls 10 and 11. Closing the other end of the casing comprising said parts 1 and 9 is a cover plate 12 likewise bolted or otherwise secured in place.

Non-rotatably fitted into such cylindrical chamber by keying, force fit or like expedient is a sleeve 14 and annular liners or plates 15 and 16 at opposite ends thereof, said sleeve and plates preferably being made of graphite, for example, or if desired from any other material having required properties.

40 As best shown in Figs. 3 and 4, said sleeve 14 is formed with a pair of diametrically opposed openings 17 through the wall thereof which register with one of the undercuts 3—4 and with another pair of diametrically opposed openings 18 through the wall thereof which register with the other of said undercuts 3—4. Said openings are circumferentially spaced to provide relatively narrow barriers 19 therebetween.

45 The bore through said sleeve 14 is of an oblong form consisting of a pair of cylindrical sections 20 and 21 having parallel axes 22 and 23 respectively and intersecting along the lines 24 in barriers 19. The wall of such sleeve bore is preferably formed with a large number of fine grooves

or serrations from one end to the other to provide, as will hereinafter more specifically be pointed out, a series of dams or channels which are operative to effectively resist leakage of fluid therewith even though appreciable clearance is provided between the ribs of said grooves or serrations and the ribs of the correspondingly serrated or grooved outer surface of the pump assembly now to be described. The term "fine grooves or serrations" as herein used indicates grooves of .001 to .010 inch depth for example and spaced apart a like distance to provide ribs of corresponding width and height, and the term "appreciable clearance" likewise covers a range from about .001 to .010 inch.

Journalled in the pump casing as on bearings 25 for rotation about axis 23 is a shaft 26 which has secured at one end thereof as by the pin 27 a pump member 28. Said pump member 28 is in the form of a cross-head including a hub 29 in which the ends of said pin 27 are anchored, and radially extending arms 30 terminating in diametrically opposed segments 31 of diameter corresponding generally with the diameter of the cylindrical section 21 of the sleeve bore. The outer cylindrical surfaces of said segments 31 are also preferably formed with a series of fine grooves or serrations which operate in the manner previously indicated to eliminate flow of fluid between the segments 31 and the cylindrical section 21 of said sleeve bore. By so scarfing the pump member 28 and sleeve 14 the clearance space between the peaks or ribs of the scarfed surfaces may be spaced apart several thousandths of an inch as indicated whereas pumps usually require the maintenance of a very close clearance, usually less than one-thousandth of an inch. Said segments 31 extend from one liner plate 15 to the other liner plate 16 and have a running fit therebetween.

Also journalled in said pump casing as on bearings 32 is another shaft 33 which may be integrally formed with a cross-head constituting another pump member 34, said pump member comprising arms 35 terminating in diametrically opposed segments 36 of the same form as the segments 31 previously described. The outer cylindrical surfaces of said segments 36 are again preferably scarfed or serrated and the end faces of said segments 36 again having a running fit between said liner plates 15 and 16. Said shaft 33 rotates about the axis 22 and likewise the segments 36 have outer cylindrical surfaces which are coaxial with the cylindrical section 20 of the bore sleeve 14 and of diameter generally corresponding with the diameter of section 20 and preferably slightly less as permitted by the scarfing of the opposed surfaces.

Between the aforesaid pump members or cross-heads 28 and 34 is a coupling block 37 which, as best shown in Fig. 2 is of rectangular cross-section or more properly of square cross-section in a plane normal to the axes of the pump members and has a bore 38 therethrough and is formed with a slot 39 thereacross which permits fitting of the block over the hub 29 and arms 30 of pump member 28 while further permitting transverse movement of said block with respect to the axis of said pump member. The opposed parallel faces 40 of said block have a relatively close sliding fit within corresponding parallel chordal faces 41 of segments 31.

Said block is also formed with another slot 42 thereacross disposed at right angles to the slot 39, said slot 42 having a loose fit over the

arms 35 and hub of pump member 34 and the opposed faces 43 of said block have a sliding fit between the chordal faces 44 of the segments 36 whereby said block may partake of transverse sliding with respect to pump member 34 along a path at right angles to the path of relative transverse sliding of said block with respect to said pump member 28.

In the embodiment of the invention illustrated in Fig. 1, the shaft 33 extends through casing part 9 and constitutes the drive shaft of the pump. However, it will be apparent that, if desired, the other shaft 26 could be extended through cover plate 12 to constitute the drive shaft of the pump.

As best shown in Fig. 3, pump members 28 and 34 and coupling block 37 constitute a pump assembly dividing the chamber in the pump casing into a plurality of independent spaces which as evident from a comparison of Figs. 3 and 4 alternately increase and decrease in size and alternately communicate with the openings 17 and 18 in sleeve 14 during rotation of the pump assembly whereby to effect intake and discharge of fluid from the respective ports 7 and 8. When the pump assembly is rotated in the direction indicated by arrow 45, the openings 17 constitute intake openings and the openings 18 constitute discharge openings and obviously the direction of rotation may be reversed to correspondingly reverse the pump.

The aforesaid spaces are formed between adjacent segments 31 and 36 which seal with the bore in sleeve 14 and end walls of plates 15 and 16 and coupling block 37 which seals with the chordal faces 41 and 44 of adjacent segments. It is preferred that block 37 be of a size such that in the position of the parts as shown in Fig. 4, a corner thereof will be in relatively close proximity to the line of intersection 24 of the cylindrical sections 20 and 21 in the bore of sleeve 14 so as to minimize leakage between openings 17 and 18 at one barrier 19 and similarly it is preferred that the segments 31 and 36 be of circumferential extent so as to substantially abut each other as they pass the intersection 24 as shown in the lower portion of Fig. 4 so as to minimize the leakage between openings 17 and 18 at the other barrier 19.

Referring again to Figs. 3 and 4, rotation of the pump assembly which comprises said pump members 28 and 34 and said coupling block 37 in the direction indicated by the arrow 45 in Fig. 3 will cause progressive enlargement of the space 46 while in communication with one opening 17 whereas the space 47 has just increased to maximum size and has been cut off from the other opening 17 by the edge of the upper segment 36 and is ready to decrease in size and to be brought into communication with the lower opening 18 by the uncovering of the latter opening by the edge of the lower segment 36. At this instant the space 48 is decreasing in size while in communication with the upper opening 18.

Referring now to Fig. 4, the pump assembly has been rotated 45° in a clockwise direction from Fig. 3 to illustrate how the spaces vary in size. In this case, the space 46 is still increasing in size while in communication with lower opening 17, such increase continuing during the next 45° rotation until said space 46 is of size the same as space 47 in Fig. 3 and cut off from openings 17 and 18 by the edges of segments 31. During the rotation of the pump assembly from Fig. 3 to Fig. 4, the space 47 decreases in

size while in communication with the lower opening 18 and the space 48 has decreased to minimum size and has been cut off from upper opening 18 by the edge of segment 31. Upon further rotation of the pump assembly from Fig. 4, said space 48 will increase in size and will be in communication with upper opening 17.

As now evident, the pump assembly divides the chamber in the pump casing into a plurality of spaces which alternately increase and decrease in size and alternately communicate with paired openings leading into the chamber to effect intake and discharge of fluid, said spaces being defined by a portion of the wall of section 20 or 21 extending from a line of intersection 24 to the edge of a segment 31 or 36 and by the outer surface of a segment eccentric with respect to the section 20 or 21 in question, the corner of the coupling block 37, and the edge of the first-mentioned segment. Of course, in some positions of the pump assembly the spaces are defined by the edges of one pair of segments 31 or 36, a portion of the wall of section 20 or 21 between such segments, the outer surface of a segment eccentric to the section in question, and two corners of coupling block 37, as for example the space 47 in Fig. 3.

It is further to be noted that by reason of the disposition of the openings 17 and 18 in sleeve 14, as shown, the load on the bearings 25 and 32 is semi-balanced.

The form of the invention illustrated in Fig. 5 is generally the same as that just described except that a shaft 50 is non-rotatably fixed as by means of a pin 51 in the pump casing part 52 and projects through one of the liner plates 53 into the chamber defined between the sleeve 54 and liner plates 53 and 55. On such projecting end of said shaft 50 is a bushing 56 of desired bearing material and rotatable on said bushing is a pump member 57 of the form substantially the same as pump member 28 in Fig. 2.

Another shaft 58 is rotatable in a similar bushing 59 about an axis parallel to the axis of shaft 50, said shaft extending through a cover plate 60 secured as by bolts 61 to pump casing part 52 to thus constitute the drive shaft. Here again the drive shaft 58 is formed with a pump member 62 in the form of a cross-head substantially as shown at the right-hand side of Fig. 2. Again interposed between these intersecting pump members 57 and 62 to form a sliding coupling is a coupling block 63 of form similar to block 37 as illustrated in the middle of Fig. 2, said pump members 57 and 62 being of diameter corresponding to the diameters of intersecting cylindrical wall sections in sleeve 54 having parallel axes.

Insofar as the basic principle of operation is the same as for the pump illustrated in Figs. 1-4, the operation of the Fig. 4 modification need not be repeated. As before, the pump casing part 52 is formed with ports 64 and 65 each of which has a passage 66 and 67 respectively leading to the undercuts 68 and 69 formed in casing bore 70, said undercuts 68 and 69 communicating with respective pairs of diametrically opposed openings formed through the wall of sleeve 54.

As apparent to those skilled in the art, the porting of the pump may be arranged in any number of different ways too numerous to illustrate and describe. It will further be understood by those skilled in the art that the pump chamber in which the pump members 28, 34, and 57, 62 are disposed may constitute opposed axially

spaced walls of the pump casing parts with the special form of peripheral wall of the pump chamber formed directly in a pump casing part rather than in a sleeve inserted therein. However, as before indicated, it is preferred to form the pump chamber from sleeves and end liner plates to enable desired selection of materials therefor and to facilitate replacement due to wear or damage. Moreover, by employing a separate sleeve, the special bore therethrough may be more readily formed.

Other modes of applying the principle of the invention may be employed, change being made as regards the details described, provided the features stated in any of the following claims, or the equivalent of such be employed.

I therefore particularly point out and distinctly claim as my invention:

1. A rotary pump comprising a casing provided with a chamber and fluid inlet and discharge ports leading into such chamber, and a pump assembly rotatable within such chamber and dividing such chamber into a plurality of spaces which alternately increase and decrease in size and alternately communicate with such ports during rotation of said assembly, the peripheral wall of such chamber including intersecting sections of circular transverse cross-section struck from spaced and parallel axes, and said assembly comprising intersecting members mounted in said casing for rotation about axes respectively coinciding with the axes of the aforesaid sections of the peripheral wall of such chamber and of diameter substantially the same as the respective sections, and a coupling block having a non-rotatable and transversely slidable connection with said members and forming therewith and with such chamber such plurality of spaces, and drive means for rotating said assembly in said casing.

2. A rotary pump comprising a casing formed with a chamber which includes parallel end walls and an oblong peripheral wall consisting of two intersecting sections of circular transverse cross-section struck from spaced and parallel axes and with fluid inlet and discharge ports leading into such chamber, and a pump assembly rotatable within such chamber and dividing the same into a plurality of spaces which alternately increase and decrease in size and alternately communicate with such ports during rotation of said assembly, said assembly comprising intersecting members mounted in said casing for rotation about axes respectively coinciding with the axes of the aforesaid sections of the peripheral wall of such chamber and of diameter substantially the same as the respective sections, and a coupling block having a non-rotatable and transversely slidable connection with said members and forming therewith and with such chamber such plurality of spaces, and drive means for rotating said assembly in said casing.

3. A rotary pump comprising a casing formed with a chamber which includes parallel end walls and an oblong peripheral wall consisting of two intersecting sections of circular transverse cross-section struck from spaced and parallel axes and with fluid inlet and discharge ports leading into such chamber, and a pump assembly rotatable within such chamber and dividing the same into a plurality of spaces which alternately increase and decrease in size and alternately communicate with such ports during rotation of said assembly, said assembly comprising intersecting members mounted in said casing for rotation

about axes respectively coinciding with the axes of the aforesaid sections of the peripheral wall of such chamber and of diameter substantially the same as the respective sections, and a coupling block having a non-rotatable and transversely slidable connection with said members and forming therewith and with such chamber such plurality of spaces, and drive means for rotating said assembly in said casing, each of said members comprising a cross head formed with diametrically opposed segmental sections extending from one end wall to the other of such chamber, and said coupling block being of rectangular cross-section with opposite faces transversely slidably fitted within the segmental sections of the respective members.

4. A rotary pump comprising a casing formed with a chamber which includes parallel end walls and an oblong peripheral wall consisting of two intersecting sections of circular transverse cross-section struck from spaced and parallel axes and with fluid inlet and discharge ports leading into such chamber, and a pump assembly rotatable within such chamber and dividing the same into a plurality of spaces which alternately increase and decrease in size and alternately communicate with such ports during rotation of said assembly, said assembly comprising intersecting members mounted in said casing for rotation about axes respectively coinciding with the axes of the aforesaid sections of the peripheral wall of such chamber and of diameter substantially the same as the respective sections, and a coupling block having a non-rotatable and transversely slidable connection with said members and forming therewith and with such chamber such plurality of spaces, and drive means for rotating said assembly in said casing, each of said members comprising a cross head formed with diametrically opposed segmental sections extending from one end wall to the other of such chamber, and said coupling block being of rectangular cross-section with opposite faces transversely slidably fitted within the segmental sections of the respective members, said coupling block being of such size that the corners thereof pass in close proximity to the lines of intersection of the aforesaid sections of such chamber during rotation of said pump assembly.

5. A rotary pump comprising a casing formed with a chamber which includes parallel end walls and an oblong peripheral wall consisting of two intersecting sections of circular transverse cross-section struck from spaced and parallel axes and with fluid inlet and discharge ports leading into such chamber, and a pump assembly rotatable within such chamber and dividing the same into a plurality of spaces which alternately increase and decrease in size and alternately communicate with such ports during rotation of said assembly, said assembly comprising intersecting members mounted in said casing for rotation about axes respectively coinciding with the axes of the aforesaid sections of the peripheral wall of such chamber and of diameter substantially the same as the respective sections, and a coupling block having a non-rotatable and transversely slidable connection with said members and forming therewith and with such chamber such plurality of spaces, and drive means for rotating said assembly in said casing, each of said members comprising a cross head formed with diametrically opposed segmental sections extending from one end wall to the other of such chamber, and said coupling

block being of rectangular cross-section with opposite faces transversely slidably fitted within the segmental sections of the respective members, the segmental sections extending circumferentially to a degree such that the edges of adjacent sections periodically substantially abut at the lines of intersection of the aforesaid sections of such chamber during rotation of said pump assembly.

10 6. A rotary pump comprising a casing provided with a chamber and fluid inlet and discharge ports leading into such chamber, and a pump assembly rotatable within such chamber and dividing such chamber into a plurality of spaces which alternately increase and decrease in size and alternately communicate with such ports during rotation of said assembly, the peripheral wall of such chamber and the opposed surfaces of said pump assembly which define such spaces being formed with a series of grooves extending generally lengthwise of the axis of rotation of said pump assembly whereby appreciable clearance may be provided without corresponding leakage of fluid between such spaces and between such ports.

20 7. A rotary pump comprising a casing formed with a cylindrical chamber therein having parallel end walls and with fluid intake and discharge ports leading to such chamber, a sleeve in such chamber formed with two pairs of diametrically opposed openings through the wall thereof respectively in communication with such ports, the respective openings of one pair being circumferentially spaced from the openings of the other pair, said sleeve being formed with an oblong bore therethrough consisting of two parallel cylindrical sections which intersect along two lines respectively disposed between one of the openings of each pair of openings and the other of the openings of each pair of openings, a pair 30 of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing 40 whereby said pump assembly may be rotated.

50 8. A rotary pump comprising a casing formed with a cylindrical chamber therein having parallel end walls and with fluid intake and discharge ports leading to such chamber, a sleeve in such chamber formed with two pairs of diametrically opposed openings through the wall thereof respectively in communication with such ports, the respective openings of one pair being circumferentially spaced from the openings of the other pair, said sleeve being formed with an oblong bore therethrough consisting of two parallel cylindrical sections which intersect along two lines respectively disposed between one of the openings of each pair of openings and the other 60 of the openings of each pair of openings, a pair 65 of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing 70 whereby said pump assembly may be rotated.

of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross-section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing whereby said pump assembly may be rotated, said segmental sections of each member being of sufficient circumferential extent to preclude communication between successive openings in said sleeve.

9. A rotary pump comprising a casing formed with a cylindrical chamber therein having parallel ends walls and with fluid intake and discharge ports leading to such chamber, a sleeve in such chamber formed with two pairs of diametrically opposed openings through the wall thereof respectively in communication with such ports, the respective openings of one pair being circumferentially spaced from the openings of the other pair, said sleeve being formed with an oblong bore therethrough consisting of two parallel cylindrical sections which intersect along two lines respectively disposed between one of the openings of each pair of openings and the other of the openings of each pair of openings, a pair of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross-section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing whereby said pump assembly may be rotated, said segmental sections of each member being of sufficient circumferential extent so that the edges of adjacent sections substantially abut each other as they pass the lines of intersection of such cylindrical sections of such sleeve bore whereby to preclude communication between the openings on opposite sides of the lines of intersection.

10. A rotary pump comprising a casing formed with a cylindrical chamber therein having parallel end walls and with fluid intake and discharge ports leading to such chamber, a sleeve in such chamber formed with two pairs of diametrically opposed openings through the wall thereof respectively in communication with such ports, the respective openings of one pair being circumferentially spaced from the openings of the other pair, said sleeve being formed with an oblong

bore therethrough consisting of two parallel cylindrical sections which intersect along two lines respectively disposed between one of the openings of each pair of openings and the other of the openings of each pair of openings, a pair of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross-section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing whereby said pump assembly may be rotated, said coupling block being of size such that in certain positions of the pump assembly a corner of said block is in close proximity to one of the lines of intersection of such sleeve bore whereby to preclude communication between the openings on opposite sides of such line of intersection.

11. A rotary pump comprising a casing formed with a cylindrical chamber therein having parallel end walls and with fluid intake and discharge ports leading to such chamber, a sleeve in such chamber formed with two pairs of diametrically opposed openings through the wall thereof respectively in communication with such ports, the respective openings of one pair being circumferentially spaced from the openings of the other pair, said sleeve being formed with an oblong bore therethrough consisting of two parallel cylindrical sections which intersect along two lines respectively disposed between one of the openings of each pair of openings and the other of the openings of each pair of openings, a pair of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross-section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing whereby said pump assembly may be rotated, the surface of such sleeve bore and the outer cylindrical surfaces of said members being formed with a series of grooves extending from one end to the other whereby appreciable clearance may be provided without corresponding leakage between such spaces and openings.

12. A rotary pump comprising a casing formed with a cylindrical chamber therein having parallel end walls and with fluid intake and dis-

11

charge ports leading to such chamber, a sleeve in such chamber formed with two pairs of diametrically opposed openings through the wall thereof respectively in communication with such ports, the respective openings of one pair being circumferentially spaced from the openings of the other pair, said sleeve being formed with an oblong bore therethrough consisting of two parallel cylindrical sections which intersect along two lines respectively disposed between one of the openings of each pair of openings and the other of the openings of each pair of openings, a pair of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, a coupling block of rectangular cross-section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially to one of said members and extending exteriorly of said casing whereby said pump assembly may be rotated, the surface of such sleeve bore and the outer cylindrical surfaces of said members being formed with a series of grooves extending from one end to the other whereby appreciable clearance may be provided without corresponding leakage between such spaces and openings, such grooves preferably being .001 to .010 inch deep and a corresponding distance apart to define ribs therebetween whereby the clearance between the ribs in such bore and the ribs on said members may vary from .001 to .010 inch but yet without permitting excessive leakage between such spaces and openings during rotation of said pump assembly and without generating excessive frictional heat.

13. A rotary pump comprising a casing formed with a cylindrical chamber therein having parallel end walls and with fluid intake and discharge ports leading to such chamber, a sleeve

12

in such chamber formed with two pairs of diametrically opposed openings through the wall thereof respectively in communication with such ports, the respective openings of one pair being circumferentially spaced from the openings of the other pair, said sleeve being formed with an oblong bore therethrough consisting of two parallel cylindrical sections which intersect along two lines respectively disposed between one of the openings of each pair of openings and the other of the openings of each pair of openings, a pair of intersecting vane-like members journaled in said casing for rotation about axes coinciding with the axes of the respective cylindrical sections of such sleeve bore, said members each including opposite segmental sections of diameter substantially the same as the respective cylindrical section and extending from one end wall to the other of such chamber, 20 a coupling block of rectangular cross-section having its two pairs of opposed faces transversely slidably fitted within the segmental sections of the respective members, said members and coupling constituting a pump assembly and defining with such sleeve bore a plurality of independent spaces which alternately increase and decrease in size and alternately communicate with such openings responsive to rotation of said assembly, and a drive shaft connected coaxially 25 to one of said members and extending exteriorly of said casing whereby said pump assembly may be rotated, and liner plates in said casing disposed at the opposite ends of said sleeve and constituting the parallel end walls of such chamber, 30 said sleeve and liners being made of bearing material.

JAMES P. JOHNSON.
